UNITED STATES PATENT OFFICE.

JOSEPH H. BOURGON, OF DETROIT, MICHIGAN, ASSIGNOR TO THE STUDEBAKER CORPORATION, OF SOUTH BEND, INDIANA, AND DETROIT, MICHIGAN, A CORPORATION OF NEW JERSEY.

TOP CONSTRUCTION.

Application filed December 13, 1924. Serial No. 755,727.

This relates to tops for motor vehicles and the like and particularly to tops of the permanent type, and has for one of its objects to provide a permanent top frame shaped from a continuous piece of sheet metal to which the various other top frame members may be applied to form a permanent unitary structure.

Another object is to provide a permanent top shaped from a continuous sheet of metal, with transverse slots spaced at frequent intervals along the upper portion thereof, dividing the upper central surface into independent sections, one edge of the metal being displaced in forming the slot by binding the metal downwardly perpendicular to the plane of the top thus providing a means for stiffening the independent sections.

A further object is to provide a permanent top shaped from a continuous piece of sheet metal having transverse slots at spaced intervals along the upper portion thereof, the metal displaced in the forming of the slots being bent downwardly to form cross ribs, and for further strengthening the top with wooden members secured to the cross ribs to which the top inner lining is secured.

A still further object is to provide a permanent top shaped from a continuous piece of sheet metal, with a wooden cross member secured to the front portion thereof to provide a fastening means for the front top supports, the rainshield and the windshield, and to also provide a continuous wooden tacking strip along the lower edge of the top frame to which the top covering and lining can be secured.

The above being among the objects of the present invention the same consists of certain features of construction and combination of parts to be hereinafter described with reference to the accompanying drawing, and then claimed, having the above and other objects in view.

In the accompanying drawing which illustrates a suitable embodiment of the present invention, and in which like numerals refer to like parts throughout the several views,

Figure 1 is a perspective view of the finished top as it may appear upon an automobile body.

Figure 2 is a perspective view of the top frame before the top covering, lining and other finishing parts are assembled thereto.

Figure 3 is a fragmentary perspective view showing one of the slotted openings, the cross rib being formed integral therewith, and the wooden tacking strips fastened to the cross rib with the top lining secured to the tacking strips.

Figure 4 is a transverse sectional view of the structure shown in Figure 2.

Figure 5 is a longitudinal section taken through the top frame showing the top lining assembled thereto.

As shown in Figure 1, the complete top is assembled to an automobile body 11 and is supported thereon by front supports 12 and rear supporting member 13. The top frame 14 is formed to a suitable shape from a continuous piece of sheet metal, the sides of which, as shown in Figure 4, and the back are curved downwardly and have the bottom edges bent inwardly substantially perpendicular to the sides to form a horizontally extending attaching surface or flange for the continuous tacking strip 15 which extends around the sides and rear portion thereof to provide a means for tacking the edges of the top covering material thereto.

Heretofore tops of this nature, which were completely formed or covered with sheet metal, had no provision made for releasing the innumerable strains set up caused by the "weaving" of the top as the automobile of which it formed a part passes over rough and uneven roads, but in the present invention to overcome these strains and to allow the top to weave without injury thereto, a plurality of transverse slotted openings 16 are formed therein and spaced at frequent intervals in the upper portion thereof, as clearly shown in Figure 3.

In the past tops wherein the central portion is bridged by sheet metal or where the top frame is formed from a continuous sheet of metal, have not been satisfactory because of the drumming that occurs therein and the tendency of the sheet metal forming the top to vibrate in harmony with other vibrations present in the automobile of which it forms a part, much in the same way that a drum head may be made to vibrate in unison with other nearby vibrations. The slotted openings 16 mentioned in the preceding paragraph and which extend substantially across the upper surface of the top, divide this surface up into a number of independent sec-

tions thereby decreasing the tendency of the whole upper surface to vibrate or drum. To further break down the vibration or drumming, downwardly extending stiffening members or ribs 17 are provided in the upper surface of the top, or as illustrated in the several views, the metal displaced in the operation of forming the slotted openings 16 may be bent downwardly perpendicular to the plane of the top thereby forming the ribs 17. These ribs 17 cut down the tendency of the sections to vibrate by stiffening the same in a direction perpendicular to the plane of their surfaces, and in some cases it may be of an advantage to bend down both edges of the slotted openings 16 thereby strengthening the independent sections at each end.

20 A wooden crosspiece 18 may be rigidly secured to the front end of the frame 14 which provides a suitable mounting for the windshield 19 and rainshield 20 and for securing the front supports 12 thereto, as well as providing a means for securing the front end 25 of the top covering thereto.

It is possible in the present invention to provide a permanent top having the inside completely lined to give a very neat and finished appearance by securing wooden tacking strips 21 with screws 22 to each one of the cross ribs 17 which serve to stiffen the structure and to which the flap 23 sewed to the inner lining 24 may be tacked leaving no exposed tacks or screws. The lining is attached at the front to the front cross piece as shown in Figure 5, and also at the rear to the tacking strip 15 and at the sides to the tacking strips 15. Additional tacking strips such as 25 may be secured to the curved rear 40 portion to give added shape to the lining 24.

The present invention is not limited to open type automobiles as illustrated but is equally applicable to closed types of automobiles and formal changes may be made in the 45 specific embodiment of the invention described without departing from the spirit and substance of the broad invention the scope of which is commensurate with the appended claims.

50 What I claim is:—

1. An automobile top frame formed from a continuous sheet of metal to the approxi-

mate shape of a finished top and having a plurality of transverse slots formed therein extending substantially across the same, dividing the central portion of said frame into a plurality of sections connected only at the ends of said slots. 55

2. An automobile top frame formed from a continuous sheet of metal to the approximate shape of a finished top and having a plurality of transverse slots formed therein extending substantially across the same, dividing the central portion of said frame into a plurality of sections connected only at the 60 ends of said slots for strengthening said sections in a direction perpendicular to the plane of their surface. 65

3. An automobile top frame formed from a continuous sheet of metal to provide a metal top portion and integral side quarters and having a plurality of transverse slots formed in the top portion dividing the upper central portion of said frame into a plurality of sections connected only at said side quarters, 70 and a plurality of transverse ribs extending downwardly from said central portion to strengthen said sections in a direction perpendicular to the plane of their surface. 75

4. An automobile top frame formed from a continuous sheet of metal to the approximate shape of a finished top and having a plurality of transverse slots formed therein, dividing the upper central portion of said frame into a plurality of sections, transverse 80 ribs formed from the metal displaced in forming said slots, and tacking strips secured to said transverse ribs to further strengthen said independent sections in a direction perpendicular to the plane of their surface. 85

5. An automobile top frame having coved sides and a horizontally disposed upper surface formed from a continuous sheet of metal, a plurality of transverse slots formed therein, extending across said horizontal surface substantially to said curved sides, flanges adjacent one side of said slots formed from the metal displaced in forming said slots, a tacking strip secured to each of said flanges, and a top lining secured to said tacking strip. 95

Signed by me at Detroit, Michigan, U. S. A., this 5th day of December, 1924.

JOSEPH H. BOURGON.

Certificate of Correction.

It is hereby certified that in Letters Patent No. 1,600,532, granted September 21, 1926, upon the application of Joseph H. Bourgon, of Detroit, Michigan, for "Top Construction," an error appears in the printed specification requiring correction as follows: Page 2, line 66, claim 2, after the word "slots" insert the words *the metal displaced in forming said slots forming a flange on one side thereof*; and that the said Letters Patent should be read with this correction therein that the same may conform to the record of the case in the Patent Office.

Signed and sealed this 12th day of October, A. D. 1926.

[SEAL.]

M. J. MOORE,
Acting Commissioner of Patents.
